UNITED STATES PATENT OFFICE.

GEORGE W. SMITH, OF MINNESOTA LAKE, MINNESOTA.

HORSE-RELEASER.

No. 869,199.

Specification of Letters Patent.

Patented Oct. 22, 1907.

Application filed June 20, 1907. Serial No. 379,956.

To all whom it may concern:

Be it known that I, GEORGE W. SMITH, a citizen of the United States, residing at Minnesota Lake, in the county of Faribault, State of Minnesota, have invented 5 certain new and useful Improvements in Horse-Releasers; and I do hereby declare the following to be a full, clear, and exact description of the invention, such as will enable others skilled in the art to which it appertains to make and use the same.

10 This invention relates to new and useful improvements in horses releasers, and in its broad embodiment it comprises a stationary supporting device, a plate to which the whiffle tree is attached slidably connected with said supporting device and a displaceable lock 15 between the slidable plate and the supporting device.

In connection with a device constructed generally as above described the invention aims as a primary object to provide a novel construction, combination and arrangement of parts, the details of which will appear 20 in the course of the following description, in which reference is had to the accompanying drawings, forming a part of this specification like characters of reference designating similar parts, throughout the several views, wherein:—

25 Figure 1 is a side elevation showing the manner of use of a horse releaser comprehended in the present invention. Fig. 2 is an end elevation thereof. Fig. 3 is a central longitudinal section thereof. Fig. 4 is a top plan view thereof.

30 In the accompanying drawings, the numeral 1 designates a centrally located stationary part of the vehicle frame to which is secured, by means of bolts 2, a supporting member 3 the latter being provided with a longitudinal groove 4 and with flanges 5, overlying said

35 groove. Mounted for sliding movement in the groove 4, is a plate 6 having a reduced neck 7 projecting through said groove and at its front end provided with flanges 8 at each side thereof which overlie the flanges 5. The plate 6 is extended rearwardly and is provided

40 with a transverse groove 9, which, in the normal position of the parts registers with similar grooves 10, provided in the member 3 at each side thereof. A bolt 11 is employed as a pivot pin for the horizontal extension 12 of a lever 13, the latter having connection at its front 45 end with a chain 14, by means of which the device is manipulated. The lever 13 carries adjacent the extension 12 a transverse bar 15, which is designed to seat in the grooves 9 and 10 in their registering relation and to lock the plate 6 against accidental displacement.

50 The bar 15 is constructed at each side with openings 16 which surround upstanding bolts 17, carried by the member 3. Nuts 18 are threaded upon the upper ends

of said bolts and expansive coil springs 19 are interposed between the nuts 18 and the bar 15, the function of these springs being to hold said bar in position in 55 said grooves.

The plate 6 has secured thereto by means of bolt and nut fastenings 20, an angular arm 21, the upper end of which is constructed with an opening 22 to surround an upstanding post 23 carried at the front end of the 60 plate 6, a jam nut 24 being threaded upon the upper end of the post 23 and serving to hold the arm 21 in proper position. The post 23 constitutes the pivot for the whiffle tree and the arm 21 a retainer therefor.

In the course of use, should the horse become unmanageable, the driver pulls on the chain 14 and raises the lever 13 against the tension of a spring 19 and in such action moves the bar 15 out of the grooves 9 and 10, thus disrupting the interlocking engagement of the plate 6 with respect to the member 3. The horse 70 is now free to run out of the shafts of the vehicle and in such action carries the whiffle tree together with the plate 6 away from the support 3.

The horse releaser constructed in accordance with the present invention is simple in its structural details, 75 inexpensive to manufacture and practical and efficient in use.

From the foregoing description it will be seen that simple and efficient means are provided for accomplishing the objects of the invention, but while the elements herein shown and described are well adapted to serve the functions set forth, it is obvious that various minor changes may be made in the proportions, shape and arrangement of the several parts, without departing from the spirit and scope of the invention as defined in the appended claims.

What is claimed is:

A device of the type set forth, comprising a stationary supporting member having a longitudinal groove, a plate mounted for sliding movement in said groove and constructed to support a whiffle tree, said supporting member being constructed with registering transverse grooves, said plate being constructed with a transverse groove designed to register with said first named transverse grooves, a lever pivoted at its rear end to said supporting member, a transverse bar carried by said lever for engagement in said several grooves, said bar being formed with openings in the ends thereof, upstanding bolts carried by said supporting member and projecting through said openings, nuts threaded upon the upper ends of said bolts, and expansive coil springs interposed between said nuts and said bar. 90 95 100

In testimony whereof, I affix my signature, in presence of two witnesses.

GEORGE W. SMITH.
